UNITED STATES PATENT OFFICE

JAMES TORRENCE HADLY, OF BERWYN, PENNSYLVANIA

NESTED BASE FOR LAMPS, ETC.

Application filed December 23, 1931. Serial No. 582,866.

This invention is a novel improvement in nesting bases for floor or so-called "bridge" lamps, or for floor trays, stands and the like, and the principal object of the invention is to provide a pair of ornamental nesting bases, each having an upright supporting as a unit a tray and/or bridge lamp, or the like, said bases being adapted to be nested one upon the other in such manner that the combination will give the ornamental appearance of a single base unit having a pair of uprights, each supporting one or more trays and bridge lamps, said bases being readily separable when desired to use the trays and lamps as separate units in different parts of a room, or, for instance, at opposite sides of a card table.

Another object of the invention is to provide a pair of ornamental nesting interlocking bases so designed that when superimposed one upon the other the uppermost base will be prevented from lateral and rotary movement upon the lowermost base, but so designed that the upper base may be readily lifted off the lower base.

Other minor objects of the invention will be hereinafter set forth.

I will explain the invention with reference to the accompanying drawing which illustrates one practical embodiment thereof to enable others to adopt and use the same; and will summarize in the claims the novel features of construction, and novel combinations of parts, for which protection is desired.

In said drawing:—

Fig. 1 is a perspective view of the bases in nested position, each base carrying as a unit its respective upright supporting a tray and electric or other lamp.

Fig. 2 is a composite perspective view showing the bases separated.

Fig. 3 is an enlarged section on the line 3—3, Fig. 1.

Fig. 4 is an enlarged section on the line 4—4, Fig. 2.

Fig. 5 is a bottom plan view of the nested bases.

Fig. 6 is a vertical section on the line 6—6, Fig. 3.

My invention comprises a pair of ornamental nesting superimposed bases 1 and 2, the lower base 1 being shown as substantially Y-shape in plan, one leg 1a of base 1 being provided adjacent its outer end with a tapped vertically disposed bore 1b for the reception of the upright 3 threaded thereto. The end of the leg 1a is also provided with a raised lug 1c through which the bore 1b extends, the lug extending from the upper face of base 1 down around the end of the leg 1a to the bottom of the base. The outer face or contour of lug 1c is shaped to conform with the general shape and curvature of a corresponding recess in the edge of the upper nesting base 2 when superimposed thereon, whereby the bases 1 and 2 when nested as in Fig. 1 will give the appearance of a single base unit. Base 1 is provided on its underside adjacent the ends of the legs 1a, 1d, and 1e with cups 1f adapted to receive rubber or other casters for preventing injury to the floor or other surface upon which the base rests. The bore 1b extends through the cup 1f in its respective leg 1a, and in the side of the cup 1f is a hole for the passage of electric lamp wires 1x into the upright 3.

Mounted upon the upper end of upright 3 is an electric bridge lamp 4 or the like, and on the upright between the base and lamp may be clamped an ornamental tray 5 for holding cigars, ash receptacles, glasses, etc., which tray 5 may be either adjustably or fixedly secured to the upright.

The upper base 2 is preferably concavo-convex and of circular plan, having a substantially flat top with rounded edges and substantially vertical sides. Base 2 is adapted to be superimposed upon the lower base 1 and the outer ends of the legs 1a, 1d, 1e of the base 1 are adapted to fit closely against the inner periphery of the sides of the upper base 2 as shown in Fig. 5 to prevent lateral movement between the bases. In the edge of the upper base 2 is a recess 2a conforming with the shape of the lug 1c on lower base 1, whereby when the bases are superimposed the outer face of lug 1c will lie substantially flush with the corresponding portions of the 100

outer surface of the base 2, as shown in Figs. 1, 3 and 6, giving the nested bases the appearance of a single base unit; and the lug 1c engaging recess 2a prevents rotary movement between the bases.

In the base 2 diametrically opposite the recess 2a is a tapped hole 2c adapted to receive the threaded lower end of a hollow upright 6 carrying a tray 7 and bridge 10 or other lamp 8, similar to those carried by upright 3. The lower edges of the sides of base 2 may if desired be provided with short depending lugs 2b forming legs. An ornament 9 may be mounted at the center of the 15 base 2 for the purpose of enhancing the appearance thereof.

As will be noted from Fig. 5, since the lower base member is Y-shaped the lower base member does not extend under the 20 threaded connection of the standard 6 to the base 2 and ample space is provided for the passage of the electric lamp wires 2x into the upright 6. While I have shown base 1 as being Y-shaped and base 2 circular in 25 plan, I do not limit my invention to such shapes, for obviously base 1 might be made triangular in plan or any other shape which would similarly fit under the base 2 which may be made square, rectangular, oval, or 30 or of any other shape.

When nested, the base 2 fits snugly over and around the base 1, preventing lateral play between the members and the nested bases give the appearance of a unitary structure, while permitting the upper base 2 to be readily lifted off the lower base 1 when 35 it is desired to separate the lamp units. Also the engagement of lug 1c of base 1 with the recess 2a of the base 2 prevents 40 rotary movement of the upper base 2 upon the lower base, and moreover insures that the bases will always be nested together in the same proper relation.

The trays 5 and 7 on the respective standards 3 and 6 are disposed at different eleva- 45

tions so as not to interfere when the bases are assembled; also the lamps 4 and 8 are disposed at different elevations for the same purpose.

Each base carries a complete bridge lamp 70 unit, and the base of each unit is preferably finished in ornamental manner, and when the bases are separated no unfinished or unsymmetrically shaped parts are visible.

The invention is particularly adapted for 75 use in connection with card tables, and the bases may be separated and the units placed at opposite corners or sides of the table; or the bases may be nested and the combined 80 unit used as a double or single bridge lamp depending on whether one or both lamps are lighted.

While I have illustrated my nested bases in a lamp structure, I do not limit my invention to such use for obviously the nested 85 bases may be used in connection with supports for racks, trays, or other household articles.

I claim:

1. A hollow base having sides and having 90 a notch extending inwardly through one side; an upright on the base; said base being adapted to nest a complementary base carrying an upright extending through the notch, the sides of the hollow base engaging 95 the complementary base and centering the latter therein.

2. A base of substantially circular plan having a downwardly extending peripheral flange and having a notch extending in- 100 wardly from its edge; an upright on the base adjacent its periphery disposed opposite to the notch; said base being adapted to nest a complementary base carrying an up- 105 right extending through the notch, the flange engaging the complementary base and centering the latter therein; and the complementary base having a raised lug adapted to fill the notch.

JAMES T. HADLY. 110
